UNITED STATES PATENT OFFICE

2,033,903

ICE SHAVING MACHINE

Ralston Smith, Oakland, Calif.

Application August 18, 1931, Serial No. 557,813
Renewed July 24, 1935

6 Claims. (Cl. 83—62)

This invention relates to ice shaving machines of the type described and claimed in my copending application entitled "Ice shaving machines," filed February 3, 1931, Serial Number 513,127, now matured into Patent No. 1,992,783, dated February 26, 1935.

It is the principal object of the present invention to provide ice shaving machines of the character referred to with improved dispensing and controlling mechanisms to adapt such machines for efficient operation in dispensing shaved ice into containers for chilling beverages.

In carrying the invention into practice the ice shaving machine is equipped with an ice shaving mechanism which is operated by an electric motor. This mechanism is enclosed and when in operation is capable of discharging the shaved ice through a dispensing nozzle. The nozzle is equipped with an operative gate or closure and the motor is equipped with a control mechanism. This gate and control mechanism is capable of operation by a container, when the latter is positioned to receive ice from the nozzle, to open the gate and close the motor circuit. When the container is removed from this position the gate closes and the motor circuit is automatically opened.

One form which the invention may assume is exemplified in the following description and illustrated by way of example in the accompanying drawings, in which:

Fig. 1 is a view in elevation of an ice shaving machine embodying the invention.

Fig. 2 is a plan section taken on line II—II of Fig. 5.

Figs. 3 and 4 are views in elevation of the motor control switch.

Fig. 5 is a view in elevation and section of the ice shaving machine.

Fig. 6 is a plan section taken on line VI—VI of Fig. 5.

Figs. 7 and 8 are fragmentary prospective views disclosing the manner in which the gate and motor control mechanism are operated by the container.

Referring more particularly to the accompanying drawings 10 indicates an ice shaving machine comprising a suitable hollow base 11 and an ice receiving chamber or column 12 mounted thereon. An ice shaving mechanism 14 is mounted at the upper end of the base and within the lower end of the ice receiving chamber, which mechanism, when operated is capable of finely dividing ice deposited in large pieces in the chamber and discharging ice shavings outwardly through a

nozzle 15 which extends outwardly from the chamber or column 12.

The ice shaving mechanism 14 is operated by an electric motor 16 mounted within the base 11. The circuit of this motor is controlled by a switch illustrated in Figs. 3 and 4, which switch includes a pair of stationary terminals 17 and a reciprocable switch blade 18. Springs are provided which normally tend to maintain the switch blade 18 out of contact with the terminals 17 and thereby normally maintain the motor circuit open.

To close the switch, I provide a control mechanism which includes a vertical control rod 19, the lower end of which is provided with an arm 20 associated with the switch blade 18 in a manner that when the rod is revolved and the arm 20 is swung in one direction, it will move the switch blade 18 into contact with the terminal 17 and complete the motor circuit. The control rod 19 is rotatably mounted and is suitably supported by the base 11.

The upper end of the control rod 19 projects outwardly from the base as illustrated clearly in Figs. 1, 7 and 8 and is positioned at a spaced distance from the nozzle. The upper extremity of this control rod 19 is bent at right angles to the axis of the rod so that it may be engaged and turned to operate the switch.

The outer end of the nozzle 15 is fitted with a laterally extending guide 20a on which a gate or closure 21 is slidably mounted. This gate or closure has a pair of lugs 22 projecting outwardly therefrom which may be engaged by a container as illustrated in Fig. 7.

The gate or closure 21 is also provided with a finger 23 which is adapted to engage the upper end of the motor switch control rod 19 to turn the same sufficiently to close the motor switch when the gate 21 is moved to a position opening the nozzle.

In operation of the device, ice in large pieces is deposited in the ice receiving chamber 12 and when it is desired to deposit shaved ice in a glass or other container, the glass is positioned substantially as shown in Fig. 7 with the edge of one wall interposed between the lugs 22. Lateral movement is then imparted to the glass to move the gate laterally of the nozzle or spout 15. This movement will open the gate 21 and at the same time cause engagement between the finger 23 and the outwardly turned end of the control rod 19. This will impart a rotary movement to the control rod 19 and through the medium of arm 20 close the switch by engaging the switch blade 18 with the terminals 17. Thus, the motor will com-

mence operating to shave the ice and such shaved ice will discharge through the nozzle 15 into the glass. When sufficient ice has been discharged into the glass, lateral movement of the glass to the left will simultaneously position the gate 21 to close the nozzle and enable the spring means to open the motor control switch and stop the motor.

It is obvious from the foregoing that by the 10 present invention I have provided a very simple control mechanism for ice shaving machines which enables an operator to rapidly and efficiently fill the containers with shaved ice and further that the mechanism is so arranged that 15 the motor is only in operation when shaved ice is desired and that the discharge nozzle is only open when there is a container positioned to receive the ice therefrom.

While I have shown the preferred form of my 20 invention, it is to be understood that various changes may be made in its construction by those skilled in the art without departing from the spirit of the invention as defined in the appended claims.

25 Having thus described my invention, what I claim and desire to secure by Letters Patent is:

1. An ice shaving machine of the character described comprising an ice shaving mechanism, an electric motor for operating said mechanism, 30 a nozzle through which ice is discharged by operation of said mechanism, an operative gate controlling the nozzle, a switch for controlling the motor, a switch operating mechanism for operating the switch, projecting means on said gate 35 adapted to be engaged by a container whereby the gate may be operated by the positioning and removal of the container from alignment with the nozzle said gate having a projecting portion, said switch operating mechanism lying in the path of movement of said projecting portion on the gate whereby opening of the gate will be accompanied by closing of the switch.

2. In an ice shaving machine of the character 45 described, an ice shaving mechanism, a nozzle through which shaved ice is discharged by operation of the said mechanism, a guide means extending laterally of the nozzle at the discharged end thereof, a closure for said nozzle slidably 50 mounted on said guide for movement into and out of register with said nozzle, projections projecting outwardly from said closure and between which the edge of a container may be interposed whereby the closure may be actuated by movement of the container laterally of the nozzle.

3. The combination with an ice shaving machine comprising a container having a spout for the discharge of shaved ice, a slidable closure member for said spout, a pair of lugs extending outwardly from said closure member to receive the edge of a receptacle whereby the closure may be opened and closed by engaging said receptacle with said lugs and moving the receptacle laterally of the spout, means for shaving ice, an electric motor for operating said means, and a normally open switch mechanism adapted to be closed by opening of said closure member to place said electric motor into operation by opening of the closure member, means on said closure member contacting said switch mechanism when said closure is in open position.

4. An ice shaving machine of the character described comprising an ice shaving mechanism, an electric motor for operating the same, a nozzle through which shaved ice is discharged by 20 the operation of said mechanism, an operative closure for said nozzle, an operative control mechanism for said motor, and means on said closure and control mechanism enabling the same to be operated together by a container when the latter 25 is positioned to receive ice from the nozzle.

5. An ice shaving machine of the character described comprising an ice shaving mechanism, an electric motor for operating the same, a nozzle through which shaved ice is discharged by the operation of said mechanism, an operative closure controlling the discharge of ice through said nozzle, an operative switch operating mechanism for controlling the motor, said closure and said switch operating mechanism being provided with elements positioned to engage whereby movement of the closure to open position will be accompanied by operation of the switch operating mechanism to place the motor in operation.

6. An ice shaving machine of the character 40 described comprising an ice shaving mechanism, an electric motor for operating said mechanism, a control switch for said motor, a nozzle through which shaved ice is discharged by operation of said mechanism, a normally closed gate controlling the nozzle, a switch operating mechanism for operating the motor switch and normally tending to maintain said switch open, said gate and switch operating mechanism being provided with means adapted to engage as the gate is being moved to open position whereby opening of the gate will be accompanied by operation of said switch operating mechanism to close the switch.
